UNITED STATES PATENT OFFICE.

EUGENE EARL NORTON, OF BRIDGEPORT, CONNECTICUT, ASSIGNOR, BY MESNE ASSIGNMENTS, TO RUDOLPH DUGAN, OF ROSLYN, NEW YORK.

SPEED-CONTROLLER.

1,110,293.

Specification of Letters Patent. Patented Sept. 8, 1914.

Application filed October 13, 1908. Serial No. 457,469.

To all whom it may concern:

Be it known that I, EUGENE EARL NORTON, a citizen of the United States, and a resident of Bridgeport, in the county of Fairfield and State of Connecticut, have invented certain new and useful Improvements in Speed-Controllers, of which the following is a specification.

This invention relates to a speed controller, which is specially applicable to moving picture machines, so that the film sprocket drums and other appurtenances thereof will be operated at a uniform speed, irrespective of the variations in the speed of the driving shaft of the speed controller.

The invention is exemplified in the accompanying drawings, and in which—

Figure 1 represents a partial side view of a picture machine with the invention, Fig. 2 shows a plan view of Fig. 1, Fig. 3 represents a side view of the invention with the picture machine viewed from the side opposite to that shown in Fig. 1, Fig. 4 shows a fragmentary enlarged portion of Fig. 2, Fig. 5 is a partial section of Fig. 4 on the line 5—5, and Fig. 6 shows an enlarged partial section of Fig. 2 on the line 6—6.

The invention is shown with a fragmentary portion of a picture machine comprising the housing 15 with the upper reel case 16 for the film 17. The housing is carried on legs 18 that are supported on the base plate 19 and to the lower face of the latter is attached the lower reel case 20.

On the base plate 19 is located a frame 21 with the side plates 22, 23 and 24. In the side plates 22, 23 is journaled the driving shaft 25 with the driving crank 26, having the handle 27 at one end and the grooved pulley 28 and the spur gear 29 at the other end thereof. The pulley 28 carries a belt 30 that connects with a pulley not shown on the lower reel case 20.

A second shaft 35 is journaled in the side plates 22, 23 on which is fastened at one end the pinion 36 the teeth of which mesh with the teeth of the pinion 37, that is journaled on a pin 38 extending from the side plate 23. On the opposite end of the second shaft 35 is secured the spur gear 40, the teeth of which mesh with the teeth of the pinion 41 journaled on the pin 42 extending from the side plate 22. To the pinion 41 is fastened the spur gear 43.

In the side plate 22 is journaled an abutting journal sleeve 45 with the flange 46 and collar 47. A governor is shown with the shaft having the square portion 48 and cylindrical ends 49 and 50. The cylindrical end 49 is fastened in the sleeve 45 and the end 50 is journaled in the side plate 24, a collar 53 being fastened to the said cylindrical end 50. A fly wheel 51 with the pinion 52 is journaled on the end 49, and the teeth of said pinion mesh with the teeth of the spur gear 43. On the square portion 48 of the governor shaft are slidably supported the grooved sleeve 54 with the groove 55 at one end, and the disk sleeve 56 at the other end. The latter has fastened to its outer face the disk 58 of leather or the like material, which bears against the opposing face of the fly-wheel 51, and the outer face of the grooved sleeve 54 bears against the opposing face of the collar 53. The sleeves 54 and 56 are connected by the flexible bands 57 which carry the weights 60, and the collar 53 is located so that the flexible bands 57 are always maintained in tension to always secure contact between the face of the fly-wheel 51 and the disk 58, so that rotation can always be transmitted between the two latter elements.

From the base of the frame 21 extends the post 65 on the top of which is pivoted, by means of the screw pin 66, the adjusting lever 67 with the central oval portion 68 and opening 69 in its swinging end.

Through the oval portion 68 extend guide pins 70 with the rollers 71, which latter are engaged by the groove 55 of the sleeve 54. A stop pin 72 with a jam nut 73 engages a threaded opening in the side plate 24, and bears against the side of the adjusting lever 67 when the latter is in its central position.

An adjusting rod 75 has at one end the knurled head 76 and at the other end the threads or screw 77. A pair of bevel disks 78 are fastened to the rod 75 and straddle the swinging end of the adjusting lever 67. The faces of the opening 69 in the lever 67 are beveled to gage with the beveled portions of the disks 78. The threads 77 of the rod 75 engage a threaded opening in the side plate 24, and the other end of said rod is supported in the bracket 79 secured to the base plate 19. A disk 85 with a detent or notch 86 is fastened to the rod 75, and a spring latch 87 with a projection 88 extends

from the base plate 19, the projection 88 being in the path of the notch 86.

On the cylindrical end 50 of the governor shaft is fastened the pinion 90, the teeth of which mesh with the teeth of the spur gear 91 journaled on a pin 92, extending from the side plate 24. The teeth of the spur gear 91 mesh with the teeth of the spur gear 93 carried on the shaft 94, one end of which latter is journaled in the side plate 24 and the other end of which is journaled in the picture machine. On the shaft 94 is also fastened a spur gear, not shown, but axially in line with the spur gear 93 and the teeth of which mesh with the teeth of the spur gear 95 of the picture machine. A pinion 96 turns with the gear 95 and meshes with teeth of the gear 97 fastened to the shaft 98. The teeth of the gear 97 mesh with the teeth of a pinion 99 carried on the shaft 100. The teeth of pinion 99 mesh with the teeth of the pinion 101 fastened on the shaft 102 of the sprocket drum 103. The teeth of the gear 93 mesh with the teeth of the spur gear 104 on the shaft 105, on which is carried the lower sprocket drum 106.

To use the invention an operator turns the driving shaft 25 by means of the crank 26, instead of attaching a crank to the shaft 98, as would be the case without the present improvements. The rotations of the shaft 25 are transmitted to the fly wheel 51 of the governor through the train of gears 29, 31, 36, 40, 41, 43 and 52. The disk 58 of the disk sleeve 56 bears against the face of the fly wheel 51 by reason of the tension of the flexible bands 57. The rotations of the said fly wheel cause the shaft of the governor to turn with a speed equal to the speed of said fly wheel or a less number of turns, depending upon the pressure between the disk 58 of the disk sleeve 56, and the opposing face of said fly-wheel 51. The rotations of the governor shaft are transmitted to the train of gears 90, 91, 93 and then to the train of gearing in the picture machine coacting therewith to the shaft 98 and other shafts of said machine. If the operator turns the crank 26 at too great a speed the weights 60 by centrifugal force will swing out and decrease the pressure between the face of the fly wheel 51 and the disk 58, by virtue of which the rotations of the governor shaft and consequently all the appurtenances of the apparatus rotated thereby, will be decreased in speed until the normal predetermined rate of speed is obtained.

By means of the adjusting rod 75 an operator by turning the head 76 disengages the spring latch 87 from the notch 86 and the adjusting lever 67 is swung in one direction or the other by reason of one of the bevel disks 78 bearing against the opposing face of the lever 67. This will cause the grooved sleeve 54 to slide on the square por-

tion 48 of the governor shaft, and either relax or increase the pressure between the face of the disk 58 and the fly wheel 51, detracting from or assisting the effect of the centrifugal force of the weights 60 of the governor. There is thus secured means to control and adjust said governor, so that it will govern at different speeds. By this means with the same speed of the driving shaft 25, various uniform speeds may be imparted to the appurtenances of the picture machine, and the film 17 can be moved at the most desirable speed through the machine and which speed can be varied. The stop pin 72 prevents the adjusting lever 67 from being swung too far, so as to obviate excessive pressure between the outer face of the grooved sleeve 54 and the collar 53, and which excessive pressure would prevent the rotation of the governor shaft and its appurtenances. The abutting journal sleeve 45 takes the end thrust of the hub of the pinion 52.

Having described my invention, I claim:

1. The combination with a driven machine of a rotary shaft therefor, a driving shaft, a governor shaft journaled adjacent to the driving shaft, a fly wheel on the governor shaft, gearing interposed between the said fly wheel and driving shaft, a disk sleeve and a grooved sleeve slidably supported on the the governor shaft, flexible bands connecting the sleeves, the outer face of the disk sleeve bearing against the opposing face of the fly wheel, weights on the flexible bands, an adjusting lever, pins extending from the latter, engaging the grooved sleeve, means to directly move the adjusting lever to different positions, and gearing interposed between the governor shaft and the rotary shaft of the driven machine.

2. The combination with a driven machine of a rotary shaft therefor, a driving shaft, a governor shaft journaled adjacent to the driving shaft, a fly wheel journal on the governor shaft, gearing interposed between the said fly wheel and driving shaft, a disk sleeve and a grooved sleeve slidably supported on the governor shaft, flexible bands connecting the sleeves, the outer face of the disk sleeve bearing against the opposing face of the fly wheel, weights on the flexible bands, an adjusting lever, pins extending from the latter engaging the grooved sleeve, an adjusting rod engaged with the adjusting lever to directly move it in opposite directions, a disk having a notch on the said rod, a spring latch in the path of the said notch, and gearing interposed between the governor shaft and the rotary shaft of the driven machine.

3. The combination with a driven machine of a rotary shaft, a speed controller for the machine, a base plate for the controller, a frame on the base plate, side plates extend-

ing from the frame, a driving shaft journaled in the side plates, a sleeve in one of the side plates, a governor shaft with one end journaled in one of the side plates and the other end thereof fastened in said sleeve, a fly wheel journaled on the governor shaft, gearing interposed between the fly wheel and the driving shaft, a grooved sleeve and a disk sleeve slidably supported on the governor shaft, flexible bands connecting the sleeves, weights fastened to the bands, a post extending up from the frame, an adjusting lever with a central oval portion and an opening at its swinging end pivoted on said post, an adjusting rod with threads at one end engaging a threaded opening in one of the said plates of the frame, a bracket extending from the base plate supporting the other end of the adjusting rod, a disk having a notch on the said rod, a spring latch supported on the base plate, a projection on the spring latch in the path of the notch on the said disk, a train of gearing connecting the said driving shaft with the rotary shaft of the driven machine, and a pair of disks on the adjusting rod which straddle the adjusting lever to directly move it in opposite directions.

4. In a speed controller the combination of a driving shaft, a governor shaft journaled adjacent thereto, a fly wheel journaled on the governor shaft, a train of gearing between the driving shaft and the fly wheel, a disk sleeve, and a second sleeve slidably supported on the governor shaft, the disk sleeve with its outer face located to bear

against a face of the fly wheel, a collar fastened to the governor shaft located to bear against the outer face of the second sleeve, flexible bands connecting the sleeves, weights on the bands, an adjusting lever in connection with the second sleeve, a stop pin in the path of the adjusting lever and means to directly adjust said lever.

5. In a speed controller the combination of a frame, a driving shaft journaled in the frame, an abutting sleeve journaled in said frame, a governor shaft with one end journaled in one side of said frame and the other end fastened in said abutting journal sleeve, a fly wheel journaled on the governor shaft, a pinion extending from the outer face of the fly wheel, the outer face of the latter abutting against the abutting journal sleeve, a disk sleeve and a second sleeve slidably supported on the governor shaft, the disk sleeve with its outer face located to bear against the inner side face of the fly wheel, a collar fastened to the governor shaft located to bear against the outer face of the second sleeve, flexible bands connecting the sleeves, weights on the bands, an adjusting lever in connection with the second sleeve, a stop pin in the path of the adjusting lever and means to directly adjust said lever.

Signed at borough of Manhattan in the county of New York and State of New York this 6th day of October A. D. 1908.

EUGENE EARL NORTON.
